To all whom it may concern:

Be it known that I, GUSTAV FUCHS, a citizen of the United States, residing at Chicago, in the county of Cook and State of Illinois, 5 have invented a certain new and useful Design for Cigar-Boxes; and I do hereby declare the following to be a full, clear, and exact description of the invention, such as will enable others skilled in the art to which it appertains to 10 make and use the same.

The design consists in novel ornamentation for a cigar-box, as hereinafter set forth, and shown in the accompanying drawing.

Said drawing is a perspective view of a 15 cigar-box constructed in accordance with my invention.

The said drawing shows a cigar-box of rectangular shape having a surface divided into rectangular spaces by a conventional configu-

ration representing lines passing around the 20 box in both transverse and longitudinal direction and having the representation of a raised seal at one end of the box. The effect produced is novel and ornamental, the appearance presented to the eye being a cigar- 25 box whose surface is divided into rectangular spaces in a harmonious manner. The arrangement is ornamental, and the same is effective, agreeable, and pleasing to the eye.

I claim as my invention—

The design for a cigar-box, substantially 30 as shown and described.

In testimony whereof I affix my signature in presence of two witnesses.

GUSTAV FUCHS.
